UNITED STATES PATENT OFFICE.

HANNIBAL I. KIMBALL, OF NEW YORK, N. Y., ASSIGNOR TO THE NEUCRAFT COMPANY, OF NEW YORK, N. Y., A CORPORATION OF NEW YORK.

ROLLING-PRESS.

No. 851,094.

Specification of Letters Patent.

Patented April 23, 1907.

Application filed February 12, 1906. Serial No. 300,589.

To all whom it may concern:

Be it known that I, HANNIBAL I. KIMBALL, a citizen of the United States, residing in the borough of Manhattan, in the county of New York, city and State of New York, have invented certain new and useful Improvements in Rolling-Presses, of which the following is a specification.

This invention relates to roller presses that form characters in printing plates by the rolling movement of a die, or a series of dies over the plate.

One of the objects of the invention is to produce an improved means for causing the die holding member to have a true rolling movement over the engraving plate, and to be pressed into proper engagement with the plate.

Another object of the invention is to provide in such a device a die holder that will carry a series of dies constituting a font of type, which type is shiftable to bring any one of them to a printing position, and thereupon such selected type or die is advanced to a position to engage the printing plate upon the die holder being operated.

Another object of the invention is to provide improved means for shifting the engraving plate relative to the operating position of the selected die in the holder; and to further provide this latter means with mechanism whereby the said plate can be advanced either a certain unit distance or a multiple thereof, to accommodate the different widths of the characters of the several dies.

A roller press embodying my invention is set forth in the accompanying drawings whereon Figure 1 shows the device in front elevation, certain portions being broken away to disclose other portions. Fig. 2 is an end view of the plate carriage shifting means. Fig. 3 is a vertical section on the line 3-3 of Fig. 1. Fig. 4 is a fragmentary perspective view showing the engagement of one end of the working member with the table. Fig. 5 is a view of a portion of the guide plate for the dies in the holder. Fig. 6 is a fragmentary view showing the pressing member and its engaging portion of the working member. Fig. 7 shows a modification of the parts shown in Fig. 6. Fig. 8 is a perspective view of one of the dies. Fig. 9 shows three dies in side elevation. Fig. 10 is a fragmentary perspective view showing the selecting of a die

and its movement to the printing position. Fig. 11 is a similar view in side elevation; and Fig. 12 is an enlarged view of the parts shown in Fig. 2.

The device as shown comprises essentially a table member T; a working member W having a rolling movement over the table; and a pressing member R operable between an arm of the table and the working member to force the die in the working member into engagement with a plate on the table when the working member is rocked. The table T is shown as one integral member or casting having plate like end members 15 and 16 connecting the table portion 17; and also provided with a longitudinal web 18 for strengthening purposes.

A carriage member 19 slides longitudinally on the table and has projections 20 and 21 sliding in grooves 22 and 23 that are formed between the table and gibbs 24 and 25. A lug 26 projects downward from the table and has a threaded aperture engaging a screw rod 27 rotatable in bearings in the end portions of the table but prevented from end wise movement. The rotation of this screw will reciprocate the table as desired. One end of the screw rod 27 projects beyond the lug member 16 and has secured thereto an operating arm 28, that may carry a handle portion 29. By turning this handle the carriage can be advanced in either direction.

A plate P to be engraved may be secured resting on the table by means of two clamp members C C.

Two rods 30 and 31 are slidably transversely in the carriage plate as shown in Fig. 3 and can be clamped in adjusted positions by means of one or more screws 32 tapped in the lower part of the carriage to engage the rod. The clamps C are secured to the front ends of the rods as shown in Fig. 3. The clamps each comprise a block 34 secured to the rod, and a piece 35 having an aperture through which passes a clamp bolt 36 screwing into a threaded aperture in the block 34. This block and piece form jaws between which the plate P is clamped by the bolt 36 as shown in Fig. 3. This mechanism forms means for advancing the plate to provide for line spacing, the plate being locked in the proper positions by the screws 36.

The working member W for carrying the dies and rocking them to give them a rolling

movement in engagement with the plate P is shown as comprising a body portion 37 connected with a handle portion 38 by web portions 39, such members being integrally connected. At each end of the body portion 37 is a disk 40 that has a rolling movement over a bearing member 41 of the table having a plane surface, so that the working member will have a cycloidal movement. The bearing portions 41 may be separate blocks suitably secured to the table and have hardened bearing surfaces to prevent wear. Suitable means are provided to prevent slip between the disk 40 and bearing surface 41, which may comprise a rack 42 secured to the block 41 and engaging with a gear segment 43 secured to the disk 40. Means are also shown to prevent end-wise movement during such rolling of the working member comprising an annular flange 44 on the disk 40 engaging a corresponding groove 45 in the block 41. This arrangement is identical at each end of the working member and table as shown in Fig. 1.

25 The body portion 37 of the working member is provided with a channel 46, shown in Fig. 4, that has a groove 47 therein. The channel is of a size to fit the dies D shown in Fig. 8, a lug d on each die engaging in the groove 47 thereby preventing the dies from moving out of the groove, permitting only a shifting movement sidewise of the dies. A strip 48 is secured to the body member 37 of the working member and has a rabbeted portion 49 to permit the travel of the dies. At the middle portion of the working member, the strip 48 is provided with a slot 50, into which a die can be moved downward to engage the plate P and impress the same when the working member is rocked. If desired a resilient pressing means may be provided for properly positioning the die in such slot by having one side of the slot 50 formed of a block 51 movable to and from the stationary wall of the slot. Another slot 52 is made in the piece 48, leaving a piece 53 that contains an aperture in which slides a pin 54. This pin also slides in a bore in the portion 55 of the piece 48; the other end of the pin being secured to the movable block 51. In the second slot 52 a coil spring 56 is connected with the pin to advance the same to move the block 51 into engagement with a die and press the latter against the opposite stationary wall of the slot. The spring 56 may engage a collar 57 fast on the rod 54, its other end abutting the portion 55 of the strip, to thereby advance the block 51.

60 An entire font of dies D may be placed in the die holder constituting the alphabet, numerals and punctuation or other desired characters. The lower portion of each die is visible at the front and each may have inscribed thereon its character, as indicated in Fig. 10. The dies may be advanced to bring

the desired one to register with the slot 50, by any suitable means, such as by inserting a rod into either end of the slot in which they operate, and pushing them along until the desired one is positioned. Each of the dies 70 has a recess 90, in its front edge that when the die is advanced to the registering position with the slot, will engage an arm 58 that is normally held in such position by a spring 59. By this means the die is prevented from falling into the slot 50 upon being brought to registering position.

75 Suitable means are provided for forcing the positioned die downward into operating position in such slot for engaging the plate P. 80 The cam 60 is secured on a spindle 61 having bearings in the portions 39 of the working member; the cam being rotatable to engage the top face of a positioned die and move it downward against the force of the spring 85 arm 58 to operating position and to retain it in such position. The cam may be operated by an arm 62 fast on the spindle 61, and projecting toward the front of the machine.

90 The carriage T has an arm 63 at the rear extending upward and then forward somewhat U-shaped and provided with a head 64 located immediately above the middle portion of the body 37 of the die carrying member, and overhanging the cam and lever device for advancing the die in the holder. The head 64 has a plane lower face 65 lying parallel with the top of the carriage, and hence with a plate secured thereon. A pressing member is interposed between the head 64 and the underlying portion of the working member and is shown as comprising a block 66 having a channeled upper portion, in which are located antifriction devices such as rollers 67 that reduce friction between the block and the head 64. and surrounding the screw rod 27. Instead of the arm 28 being fast on the screw rod, the arm may be rotatable thereon, and carry a spring pawl 71 that engages the teeth of a 5 ratchet wheel 72, the latter being secured on the screw 27. Upon rotation of the arm in one direction the pawl will engage the wheel 72 and turn the screw, but the screw will remain stationary when the arm moves in the 10 reverse direction. The arm may normally rest against a stop pin 74 on the disk 70, the ratchet teeth 75 are spaced equidistant, and upon moving the arm backward a distance of one, two or a certain number of teeth, and 15 then advancing the arm, the ratchet wheel will rotate the screw a certain known distance. On the disk 70 are indicating marks at 76, 77 and 78; and a pointer 79 on the arm 28 registers with these indications. Certain 20 characters may require a spacing of one unit distance or the distance of one tooth in which instance the pointer that normally indicates at 76 with the arm engaging the pin 74, is brought to register with the indications at 25 77. Certain other characters may require the spacing of two ratchet teeth in which case the pointer may be moved to the indication at 78 and then the arm retracted, which will advance the screw for two ratchet teeth. 30 Other characters may require three spaces and the arm is advanced to the indications at 80 and retracted, when the screw will be advanced three ratchet teeth.

If desired suitable means may be provided for preventing slip in the rolling engagement between the pressing member and the die carrier or working member. In Fig. 6 a lug 81 is shown depending from the block 66 of the pressing member on each side. 40 And a pin 82 on each side of the segment 68 engages the walls of a slot 83 in the lug 81.

A modification of the slip preventing means is shown in Fig. 7 comprising a gear tooth 84 on the pressing member that is engaged by pins 85 and 86 on the segment 68. The gear tooth having epicycloidal faces will produce a true cycloidal movement between the segment 68 and the pressing member.

Having thus described my invention, I 50 claim:

1. In a roller press, the combination of a table arranged to support a plate, a working member having means for carrying a die, means connecting the working member and the table and organized to cause the die to have a rolling movement over a plate on the table when the working member is rocked, a movable pressing member in engagement with the working member on its side opposite to the table, and means for causing the pressing member to have a rectilinear movement upon the rocking of the working member.

2. In a roller press, the combination of a 65 table arranged to support a plate, a working

member having means for carrying a die, means connecting the working member and the table and organized to cause the die to have a rolling movement over a plate on the table when the working member is rocked, a 70 movable pressing member in engagement with the working member on its side opposite to the table, means for causing the pressing member to have a rectilinear movement upon the rocking of the working member, 75 and means for adjusting a die in the die holder toward and from the table.

3. In a roller press, the combination of a table arranged to support a plate, a working member having means for carrying a die, 80 means connecting the working member and the table and organized to cause the die to have a rolling movement over a plate on the table when the working member is rocked, a movable pressing member in engagement 85 with the working member on its side opposite to the table, means for causing the pressing member to have a rectilinear movement upon the rocking of the working member, and a cam lever for adjusting a die in the die 90 holder toward and from the table.

4. In a roller press, the combination of a table arranged to support a plate, a working member having means for carrying a die, guiding means connecting the working member and the table and organized to cause the die to have a rolling movement over a plate on the table when the working member is rocked, a movable pressing member in engagement 100 with the working member on its side opposite to the table, means for causing the pressing member to have a rectilinear movement upon the rocking of the working member, and means for preventing slip between the working member and the table 105 during said rolling movement.

5. In a roller press, the combination of a table arranged to support a plate, a working member having means for carrying a die, guiding means connecting the working member and the table and organized to cause the die to have a rolling movement over a plate on the table when the working member is rocked, a movable pressing member in engagement 110 with the working member on its side opposite to the table, means for causing the pressing member to have a rectilinear movement upon the rocking of the working member, means for preventing slip between the working member and the table during 115 said rolling movement, comprising a rack secured to the table and a gear toothed segment secured to the working member and engaging such rack.

6. In a roller press, the combination of a 120 table arranged to support a plate, a working member having means for carrying a die, means connecting the working member and the table and organized to cause the die to have a rolling movement over the table when 125 130

the working member is rocked, a movable pressing member in engagement with the working member on its side opposite to the table, means for causing the pressing member to have a rectilinear movement upon the rocking of the working member, and means for preventing slip between the pressing member and the working member during the rolling movement of the latter.

10. 7. In a rolling press, the combination of a table arranged to support a plate, a working member arranged to carry a die, means connecting the table and working member and organized to cause the die to have a rolling movement over a plate on the table when the working member is rocked, a guide member located at the opposite side of the working member from the table and having a plane surface parallel with the table, and a 15 pressing member operable between the working member and said face of the guide member.

8. In a rolling press, the combination of a table arranged to support a plate, a working member arranged to carry a die, means connecting the table and working member and organized to cause the die to have a rolling movement over a plate on the table when the working member is rocked, a guide member 20 located at the opposite side of the working member from the table and provided with a plane surface parallel with the table, a pressing member operable between the working member and said face of the guide member, 25 the pressing member being provided with anti-friction bearings engaging the guide member.

9. In a roller press, the combination of a table arranged to support a plate, a working member having means for carrying a die, means connecting the working member and the table organized to cause the die to have a rolling movement over the table when the working member is rocked, a pressing member 40 having a rolling engagement with the working member, and means organized to cause the pressing member to have a rectilinear movement upon the rocking of the working member.

50. 10. In a roller press, the combination of a table arranged to support a plate, a working member having means for carrying a die, means connecting the working member and the table and organized to cause the die to have a rolling movement over the table when the working member is rocked, a pressing member having a rolling engagement with the working member on its side opposite to the table, and means organized to cause the 55 pressing member to have a rectilinear movement upon the rocking of the working member, and means for preventing slip between the working member and the pressing member during said rolling movement.

65. 11. In a roller press, the combination of a

table arranged to support a plate, a working member having means for carrying a die, means connecting the working member and the table and organized to cause the die to have a rolling movement over the table when the working member is rocked, a pressing member having a rolling engagement with the working member on its side opposite to the table, and means organized to cause the pressing member to have a rectilinear movement upon the rocking of the working member, means for preventing slip between the working member and the pressing member during said rolling movement, comprising detents secured to the working member and a gear tooth secured to the working member and engaging said detents.

12. In a rolling press, the combination of a table arranged to support a plate, a working member arranged to carry a die, means connecting the table and working member and organized to cause the die to have a rolling movement over a plate on the table when the working member is rocked, a guide member located at the opposite side of the working member from the table and provided with a plane surface parallel with a plate on the table, a pressing member operable between the working member and said face of the guide member, the working member having a curved face, and the pressing member having a plane face engaging the curved face of the working member to cause a rolling movement between such members.

13. In a rolling press, the combination of a table arranged to support a plate, a working member arranged to carry a die, means connecting the table and working member and organized to cause the die to have a rolling movement over a plate on the table when the working member is rocked, a guide member located at the opposite side of the working member from the table and provided with a plane surface parallel with a plate on the table, a pressing member operable between the working member and said face of the guide member, the working member having a curved face, the pressing member having a plane face having a rolling engagement with the curved face of the working member, and means for preventing slip between the pressing member and the working member.

14. In a rolling press, the combination of a table arranged to support a plate, a working member arranged to carry a die, guiding means connecting the table and working member and organized to cause the die to have a rolling movement over a plate on the table when the working member is rocked, a guide member located at the opposite side of the working member from the table and provided with a plane surface parallel with a plate on the table, a pressing member operable between the working member and said face of the guide member, the working mem-

- ber having a curved face, and the pressing member having a plane face having a rolling engagement with the curved face of the working member, and means for preventing slip between the pressing member and the working member comprising detents secured to the working member and a gear tooth on the pressing member and engaging said detents. 5
15. In a roller press, the combination of a table arranged to support a plate, the table having a plane bearing surface at each end, a working member having means for carrying a die, the working member having a curved surface at each end engaging said plane surfaces of the table respectively to cause the die to have a rolling movement over a plate on the table when the working member is rocked, a movable pressing member in engagement with the working member on its side opposite to the table, and means for causing the pressing member to have a rectilinear movement upon the rocking of the working member. 10
16. In a roller press, the combination of a table arranged to support a plate, the table having a plane bearing surface at each end, a working member having means for carrying a die, the working member having a curved surface at each end engaging said plane surfaces of the table respectively to cause the die to have a rolling movement over a plate on the table when the working member is rocked, a movable pressing member in engagement with the working member on its side opposite to the table, and means for causing the pressing member to have a rectilinear movement upon the rocking of the working member. 15
17. In a roller press, the combination of a table arranged to support a plate, the table having a plane bearing surface at each end a working member having means for carrying a die, the working member having a curved surface at each end engaging said plane surface of the table respectively to cause the die to have a rolling movement over a plate on the table when the working member is rocked, a movable pressing member in engagement with the working member on its side opposite to the table, and means for causing the pressing member to have a rectilinear movement upon the rocking of the working member, means for preventing slip between the table and the working member. 20
18. In a roller press, the combination of a table arranged to support a plate, the table having a plane bearing surface at each end, a working member having means for carrying a die, a working member having a curved surface at each end engaging said plane surfaces of the table respectively to cause the die to | have a rolling movement over a plate on the table when the working member is rocked, and means for preventing slip between the working member and the pressing member during the rolling movement of such members. 70
19. In a roller press, the combination of a table arranged to support a plate, the table having a plane bearing surface at each end, a working member having means for carrying a die, the working member having a curved surface at each end engaging said plane surfaces of the table respectively to cause the die to have a rolling movement over a plate on the table when the working member is rocked, means for preventing slip between the working member and the pressing member during the rolling movement of such members, comprising a gear tooth secured to the pressing member, and a pair of detents secured to the working member in engagement with the opposite sides respectively of said tooth. 75
20. In a roller press, the combination of a table arranged to support a plate thereon, the table having a plane bearing surface at each end, a working member having means for carrying a die, the working member having a curved surface at each end engaging said plane surfaces of the table, a pressing member having a rolling engagement with the working member on its side opposite the table, and means organized to cause the pressing member to have a rectilinear movement upon the rocking of the working member. 80
21. In a roller press, the combination of a table arranged to support a plate thereon, a working member provided with means for carrying a series of dies, the working member having a rolling engagement with the table, means for advancing the dies to bring any one of them into a certain position in the working member, and means for bringing such selected die into position for engaging the plate upon the working member being rocked. 85
22. In a rolling press, the combination of a table arranged to support a plate thereon, a working member having a rolling engagement with the table, the working member being provided with a guideway in which a series of dies are movable, the working member having a slotted portion along the guideway into which the dies may enter when brought to register therewith, means for yieldingly retaining the dies from entering said slot, and a cam lever arranged to engage the rear end of the positioned die to move the die into said slot to engage the plate on the table. 90
23. In a roller press, the combination of a table arranged to support a plate thereon, a working member having a rolling engagement with the table at each end thereof, the working member having a channeled portion, a series of dies slidably in said channeled portion and retained therein, the working member having a slotted portion 125

with which any of the dies may be brought to register, a cam lever arranged to engage a die registering with said slot to move the same into the slot to engage with the plate on the table upon the working member being rocked.

24. In a roller press, the combination of a table arranged to support a plate thereon, a working member having a rolling engagement with the table at each end thereof, the working member having a channeled portion, a series of dies slideable in said channeled portion and retained therein, the working member having a slotted portion with which any of the dies may be brought to register, a cam lever arranged to engage a die registering with said slot to move the same into the slot to engage with the plate on the table upon the working member being rocked, and a pressing member having a rolling engagement with the working member at its side opposite the table, and a guide member engaging the opposite face of the pressing member.

25. In a roller press, the combination of a table arranged to support a plate thereon, a working member having a rolling engagement with the table at each end thereof, the working member having a channeled portion, a series of dies slideable in said channeled portion and retained therein, the working member having a slotted portion with which any of the dies may be brought to register, a cam lever arranged to engage a die registering with said slot to move the same into the slot to engage with the plate on the table upon the working member being rocked, a guide member connected with the table and overhanging the working member, the guide member being provided with a plane face parallel with the table, and a pressing member operable between the working member and said face of the guide member, the pressing member having a rolling engagement with the working member and movable in a rectilinear path.

26. In a roller press, the combination with the table and the working member carrying a series of dies, of a carriage shiftable on the table and provided with means for supporting

a printing plate thereon, an operating-lever, and a pawl and ratchet mechanism located between the lever and the carriage, such mechanism being organized whereby the movement of the ratchet wheel from the lever for the distance of each tooth, will advance the carriage for a distance corresponding to the width of the narrowest dies. 55

27. In a roller press, the combination with the table and the working member carrying one or more dies, of a carriage shiftable on the table and provided with means for carrying a plate thereon, a ratchet wheel, a lever carrying a pawl arranged to engage the ratchet wheel, means for advancing the carriage from the rotation of the ratchet wheel, a stop arranged to limit the movement of the lever in one direction, the ratchet teeth being spaced whereby the movement of the ratchet wheel for a distance of one tooth by the operation of the lever and pawl, will advance the carriage for a distance corresponding to the distance apart of the smallest die. 60 70

28. In a roller press, the combination with the table and the working member carrying one or more dies, of a carriage shiftable on the table and provided with means for carrying a plate thereon, a ratchet wheel, a lever carrying a pawl arranged to engage the ratchet wheel, means for advancing the carriage from the rotation of the ratchet wheel, a stop arranged to limit the movement of the lever in one direction, the ratchet teeth being spaced whereby the movement of the ratchet wheel for a distance of one tooth by the operation of the lever and pawl, will advance the carriage for a distance corresponding to the distance apart of the smallest die, an indicator plate adjacent the lever on which said stop is mounted, and indications on the plate for showing the required reverse movement of the lever to engage one, two or a number of teeth and thereby advance the carriage for a unit distance or a certain multiple of the unit, to provide for dies of varying widths. 80 85 90 95
